COLOR TELEVISION SYSTEM

Alfred N. Goldsmith, New York, N. Y., assignor
to Radio Corporation of America, New York,
N. Y., a corporation of Delaware

Application August 21, 1942, Serial No. 455,556

26 Claims. (Cl. 178—5.2)

1

This invention relates to color television systems, and methods, and more particularly, to a color television method and system in which there is provided a key image to augment and improve the color rendition and brilliancy of the finally reproduced television image.

In a color television system, it is usual to employ three primary color component images superimposed either cyclically or simultaneously to reproduce a color image having the same colors as the object of which the image is a representation. Two-component color television systems are also known, but suffer from relatively inferior fidelity of color reproduction and, thus, color television systems usually employ the three-color process.

While it is theoretically possible to achieve nearly perfect color reproduction under idealized conditions by the three primary color component method, there is, actually, considerable divergence from such ideal conditions in practice, due to the fact that the analyzing filters, the spectral sensitivity of the light sensitive medium, and the spectral response characteristics of the reproducing medium, do not have the required characteristics necessary to meet the theoretical requirements for reproduction. For example, it is well known in the theory of three color reproduction that three properly chosen pure spectral colors are sufficient to reproduce substantially all of the colors lying within the trichromatic color triangle. However, light sensitive mediums have an irregular spectral response, and color reproducing mediums are far from pure spectral colors. The color filters required for analyzing the colors of the object likewise do not have sharp cutoffs with a band of uniform transmission, but have sloping cutoffs and non-uniform transmissions through the passbands. This departure from ideal conditions, therefore, tends to degrade the quality of the color reproduction.

By my invention, in which I add to the three primary color component images a neutral black and white image, I improve the color reproduction of television images by increasing the brilliancy of the highlights, and increasing the density in the shadow areas.

Moreover, by my invention in which the primary color component images are controlled in accordance with a black and white image, I also provide correction for the overlapping of filters and the departure of ideal spectral response of the reproducing medium, so as to provide purer colors with greater saturation, and with more fidelity with respect to the original colors.

2

In accordance with my invention, I provide a method and apparatus for producing a key image of substantially neutral tint which is added to the three primary color component images, and, in addition, regulate the color component images with regard to intensity under the control of the key image brightness at corresponding elemental areas. By such a method, the departure from ideal characteristics of the analyzing filters, the light sensitive characteristic of the transmitting medium, and the spectral response of the light emitted from the reproducing medium are in some measure compensated, so that essentially the distortions arising from the imperfections of the actual elements used are in part eliminated.

Moreover, the signals which are to be transmitted as representative of the key image may be derived from the infra-red, the visible, or the ultra-violet portions of the spectrum of the light reflected from the object. Alternatively, the key image may be produced from one or more of the color components scanned in any predetermined order and used to control the primary color images in any desired proportion.

The key image, moreover, may be derived by utilizing an orthochromatic image projected upon the light sensitive surface of the transmitting tube, or by direct projection of the image of the object upon the mosaic of a suitably color-sensitive transmitting tube without the interpositioning of a filter. Where cyclic transmission of the color component images is utilized, suitable delay circuits may be interposed so that the signal resulting from the key image scanning may in proper proportion be appropriately added to, or subtracted from, the image corresponding to the color component being scanned.

Accordingly, it is an object of my invention to provide an improved method of transmitting color television images.

Another object of my invention is to provide apparatus for improving the fidelity of color television images.

Still a further object of my invention is that of improving the detail, resolution and delineation of color television images by adding to the realism and naturalness of the color reproduction and, as well, by increasing the contrast and gradation ranges in color reproduction.

Yet another object of my invention is to provide the addition of a key image to color component images in additive or subtractive color television systems in which the color component images are either simultaneously scanned or cyclically scanned.

Again, it is an object of my invention to provide a key image of substantially neutral tint to be added to each group of color component pictures in a color television system.

A further object of my invention is the production of key images and the use of a color filter, which in conjunction with the chromatic photosensitivity of the mosaic produces an orthochromatic rendition of the image, that is to say, a rendition in which brightness values correspond to the apparent brightness as viewed by the normal eye, of the various colors in the scanned image field or raster.

Yet again, an object of my invention is the production of a key printer image by using a suitable filter, which, in conjunction with the chromatic photosensitivity of the mosaic of the transmitting tube, shall be predominantly responsive in the infra-red, in the visible, or in the ultra-violet portion of the spectrum.

A still further object of my invention is the electrical control of the brightness of each color component image in accordance with the key image values at the corresponding portion of the image, whereby the brightness of the color component images is suitably reduced so that the addition of the key image brightness provides a final combined color picture of correct brightness.

Another object of my invention is to provide a color television system in which key images are produced by the equalized transmission and reception of each of the tri-color component images.

Other objects of my invention will become apparent to those skilled in the art upon a reading of the following detailed description, taken in conjunction with the drawing.

In the drawing, there is shown at Fig. 1 a schematic representation of a filter disc for use in a sequential type of scanning color television system, in which there is provided an orthochromatic sector as well as a red, green and blue sector;

Fig. 2 shows in schematic form an appropriate receiver disc having a blank sector portion in addition to the red, green and blue portions:

Fig. 3 shows in block diagram form, circuit connections of apparatus for providing the key image signal and for controlling the primary color component image signals in accordance with my invention; and,

Fig. 4 is a schematic representation of a further modification of the system wherein the several component color images are simultaneously transmitted for simultaneous reproduction at receiving points and an equalized or key image corresponding to the orthochromatic image, and thus the intrinsic brilliance of the several colored images, is transmitted in a cyclic manner.

Fig. 1 shows a four-sector rotary filter disc intended to rotate before the mosaic of a suitable camera or image scanning tube at such a rate that one of the color sectors is in front of the mosaic substantially throughout the time of the scanning of the corresponding color component picture. The disc 1 is provided with four sectors, and, as an example, sector 3 may be a red filter, sector 5 a green filter, sector 7 a blue filter, while sector 9 may be an orthochromatic filter. Alternatively, of course, it will be understood that sector 9 may be an infra-red filter or an ultra-violet filter, depending upon which type of key picture production is desired, it being understood that the adjective describing the

filter describes the color of the light which is transmitted by the filter.

Moreover, it will be appreciated that alternatively the orthochromatic filter 9 may be removed and the sector occupied by this filter left blank to provide the signal for the black and white key image.

Fig. 2 shows a corresponding filter disc to be used at the receiver in register with the image reproduction. The disc 11 is provided with the red, green and blue filters, 13, 15 and 17 respectively, and a blank sector 19. The red, green and blue color component images are reproduced on the screen by the introduction of the corresponding filter sectors 13, 15 and 17, in appropriate time relation, into the optical system, whereby the individual images are viewed or projected or otherwise observed.

The key image is produced and viewed through the clear or blank sector 19 of the disc 11. The black and white image produced during this period may be formed on either a normal black and white screen of an image reproducing tube or kinescope, or equally bright images produced simultaneously on red, green or blue picture reproducing tubes or kinescopes, in the case where simultaneous projection is used.

In Fig. 3 is shown a circuit diagram for the more complicated conditions of a cyclic scanning system to produce the train of signals for both the key image and the three color component images. In Fig. 3, the image of the object to be transmitted is thrown by the optical system 21 upon the mosaic electrode 31 of an image scanning or camera tube 27. The camera or image scanning tube 27 may be of the general type known as the "Iconoscope" and described by Zworykin and others, or the scanning tube may be of the type known in the art as the image "Iconoscope" or the "Orthicon," or it may be one of the type known as the image dissector, all of which have been disclosed both directly and by footnote reference in the book "Principles of Television Engineering" by D. G. Fink and published in 1940 by McGraw-Hill Book Co. For convenience, reference herein will be made to a scanning tube of the "Iconoscope" type as illustrative of the principles of operation. The image, in traveling to the mosaic electrode 31, passes through the filter disc 25, the disc being of the form shown in Fig. 1, and driven by a motor 23. An electron gun 35 produces an electron beam which scans the mosaic 31 to provide, through the means of released electrons, the video signal, which signal is carried by the signal plate 29 to the video amplifier 39 as is well understood in the art. The deflection coils 37 serve to produce the bi-directional scanning action of the beam of electrons released from the gun 35, and the released electrons are collected by the collector electrode 33, as is also well known in the art. Deflection of the electron beam is provided by suitably energizing the deflecting coils 37 under the control of energy of predetermined wave form and frequency, as is known in the art.

A commutator device 40 is mechanically coupled to and driven in synchronism with the motor 23. The commutator 40 is provided with four segments 43, 45, 47 and 49, each of the segments being connected to a collector ring, respectively numbered 51, 53, 55 and 57. A brush 41 bears on the commutator segments and serves to furnish the video signals from the amplifier 39 to each of the collector rings in sequence. The video signals fed to the collector rings are led to

appropriate apparatus by the brushes 59, 61, 63 and 65 respectively. The brush 59 carries the signals generated by the camera or image scanning tube 27, when the orthochromatic filter 3 is in such angular position in its rotation as to be in register with the mosaic electrode 31 of the scanning tube. The brush 61 is active to supply signals to the amplifier 87 when the red filter sector 3 is in register with the mosaic of the scanning tube 27, while the brushes 63 and 65 similarly feed energy to the amplifiers 89 and 91 respectively, when the green and the blue filters are in register with the mosaic element of the scanning tube 27.

The signals representative of the orthochromatic image are fed through the orthochromatic image signal amplifier 67 and through the lead 68 to the combining amplifier unit 93, the amplifier unit 67 serving to regulate the intensity of the video signals to be transmitted representative of the orthochromatic image. A portion of the output energy from the amplifier unit 67 is fed to each of the delay networks 69, 71 and 73, which are conventionally represented.

Delay networks are, per se, well known in the art and generally comprise series inductance elements and shunt capacity elements with a suitable terminating resistance. Thus, for simplicity of disclosure, the delay networks are merely shown in schematic form, and it is to be understood that such delay circuits may, in many instances, assume the status of an artificial line with the delay characteristics a function of the delay time required.

The delay network 69 introduces a delay time of the video signals corresponding to the orthochromatic image equal to the time required to scan one picture field, while the delay networks 71 and 73 introduce a time delay equivalent to two field scannings and three field scannings respectively. The output of the delay networks 69, 71 and 73 are fed to reversing switch units 75, 77 and 79 respectively, and thence to the conventionally indicated volume controls 81, 83 and 85, which are preferably in the form of potentiometers. Each of the volume controls above named then supplies energy to the mixer and gain control amplifier units 95, 97 and 99 respectively, and the outputs of these three units are then combined with the signal corresponding to the orthochromatic image in the combining unit 93, and the combined signals thereafter fed to the transmitting channel, as indicated.

It will be understood that the combining unit 93 serves as a signal amplifier and, at the same time, provides a means to supply each train of video or image signals to the transmitter channel without interaction upon the other signal channels, and that it does not combine all of the signals simultaneously in a cyclic system.

In the operation of the system, the series of signals corresponding to the orthochromatic image are transmitted to the combining unit 93 through the conductor 68, without time delay, after amplification in the amplifier unit 67. At the completion of the scanning of the orthochromatic image, the disc 1 is turned, for instance, to such a position that the red filter 3 is intermediate the optical system 21 and the mosaic element 31 of the scanning tube 27. In this way, by means of the commutator 40 providing the desired and proper sequence of switching, the signals corresponding at the red image are then supplied by way of the brush contact 61 to the red image signal amplifier unit 87 whose output

is fed to the mixer amplifier 95, and from it to the combining unit 93 and thence to a transmission channel of any desired type and description, which has not been shown specifically.

At the same time that the signals are developed from the camera or image scanning tube 27 in accordance with the light revealed to the mosaic through the red filter 3, the signals of the orthochromatic image, as they appear in the output of the signal amplifier control unit 67, have been passed via the conductor 70 through the delay network 69 and into the reversing switch unit 75 and then through the volume control 81 to control also the mixer amplifier and gain control unit 95. The reversing switch arrangement is provided by any convenient sort of electronic arrangement and is for the purpose of determining whether or not the series of output signals representing the orthochromatic image shall tend to increase the gain in output of the mixer amplifier and gain control unit 95 or shall tend to reduce the gain. Accordingly, it being assumed that the output signals from the amplifier control unit 67 representing the orthochromatic image are delayed one field scanning period in the delay network 69, it is apparent that the arrival in the mixer amplifier 95 of the signals from the reversing switch arrangement 75 will coincide substantially in time with the initial scanning of the red image through the filter 3.

Consequently, under conditions when it is desired that provision shall be made for decreasing the gain in the mixer amplifier and gain control unit 95 with increases in signal output from the delay circuit for highlights in the scanned subject, a switch element 101 may be placed against the upper contact point indicated, so that the output signals from the delay network 69, as conventionally indicated, may pass through a single amplifier tube 102 and thence through the switch armature to the potentiometer volume control unit 81 and, by virtue of the current flowing through the tube 102, increasing with a positive signal on the control electrode thereof, as will be the tendency for the current flowing through the mixer amplifier and gain control tube 105 contained in the mixer amplifier and gain control unit 95, it is apparent that a potential drop will take place through the potentiometer 81 in such a manner that the variable contact 106 may be set so that the signals impressed upon the control electrode 107 of the tube 105 are negative in polarity when the controlling signals upon a second grid 108 of this same tube, as they are derived in conductor 109 from the amplifier 87, are positive in sign. In this way, the orthochromatic image signals may cause a reduction in the output of the mixer and gain control tube 105 of the amplifier unit 95. However, under circumstances where it is desired that the orthochromatic video signals shall increase the gain in the mixer amplifier and gain control unit 95, it is apparent that the switch armature 101 may be moved to its lowermost contact so that the signal output from the tube 102 is now fed through the reversing tube 110 to provide under the control of the orthochromatic image a reverse polarity of signals on the control electrode 107 of the amplifier tube 105 of the mixer amplifier 95. In this way, depending upon the position of the switch armature 101, the gain in the amplifier 105 may be increased or decreased under the influence of the orthochromatic signals, so that the tube 105, as it serves the mixer amplifier and

gain control tube for the red signals, will have its output energy controlled not only by the actual signals produced as output energy from the scanning tube mosaic, (and previously amplified in amplifier 81) but also will be indirectly controlled by the previously scanned orthochromatic image.

Reference now may be made to the green image signal which is derived through the green filter section 5 of Fig. 1, for instance, and amplified in the green image signal amplifier 89. A control signal for controlling this signal output has been previously fed from the orthochromatic image signal amplifier 67 by way of the conductor 78 to the delay circuit 71, wherein it is delayed a predetermined time period (in this example assumed as the period of two image or picture fields) and then impressed upon the reversing switch unit 77, the output energy from which controls the mixer amplifier 97.

The delay circuit 71, however, has a time delay twice as long as that of the delay circuit 69 since it is to control the transmission level at which the green image or picture field is transmitted, and since the green image field is assumed to follow the orthochromatic image scanning by a delay of two fields. The delay circuit 71 will correspondingly delay the signals reaching it from the orthochromatic image signal amplifier 67. Accordingly, the energy output from the reversing switch unit 77, as it is impressed upon the mixer amplifier 97 through the volume control 83, will control the output signals from the mixer amplifier 97 which represent the green image signals as impressed thereupon by way of the image signal amplifier 89.

For simplicity of understanding, the component parts herein assumed for the reversing switch unit 77 and the mixer amplifier 97 are assumed, for instance, to be substantially identical to the corresponding elements of the reversing switch unit 75 and the mixer amplifier 95, and hence, like numbers with primes added represent corresponding parts in each figure. The same will be true of the reversing switch unit 79 and the mixer amplifier 99, hereinafter to be described, except that like parts are designated by like numbers with double primes added.

Accordingly, by properly positioning the switch armature 101', the potential applied to the control electrode 107' of the mixer 105' may be made of like polarity, or opposite polarity to the signal simultaneously impressed upon the second control grid 108', as this last named signal is derived from the image signal amplifier 89, since "highlights" are generally related and occur at the same time in the orthochromatic or key image and in each of the images of the primary image colors. Accordingly, depending upon whether or not the reversing switch is in its upper or lower position will determine whether the signal output is decreased or increased, as was above explained in connection with the signals representing the red images. Likewise, with regard to the blue signals, the output of the orthochromatic image signal amplifier 67 is supplied to the delay circuit, conventionally represented at 73, and this delay circuit, in contrast to the delay circuits 69 and 71, so provides that the time delay between the arrival of the signal at the input and the arrival of the signal at the output from where it is supplied to the reversing switch unit 79 will be a time period coinciding with three picture fields, that is, for instance, the time required to scan all of the orthochromatic, the red and the green images, for instance. Otherwise,

the arrangement of the blue signal channel substantially coincides with that of the red and the green, hereinabove explained, and, accordingly, the output signal level of the mixer amplifier 95 is determined by the signals applied to each of the controlling electrodes 107'' and 108'', of which the former potential is controlled by the position of the switch armature 101'' in the reversing switch unit 79, and in which the potential of the latter control electrode is determined by the output of the blue image signal amplifier 91 as supplied to the mixer amplifier 97 by way of the conductor 111.

The output energy from the mixer amplifier 95 is fed by way of a conductor 115 to the combining amplifier unit 93. The output from the mixer amplifier 97 is fed by way of a conductor 117 to the same combining unit and the output from the mixer amplifier 99 is fed by a similar conductor 119 to the same combining unit.

From what has been indicated above, it is apparent that the sequence of energization of the combining amplifier unit 93, herein represented only schematically since all of the signals may be applied through a common amplifier channel, will first amplify the orthochromatic signals; next the red image signals; next the green image signals, and lastly the blue image signals, whereupon the cycle will be repeated. Thus, the sequence of transmission, as hereinabove explained, is cyclic, with it being understood that the orthochromatic image may, for the reasons above outlined in the statement of the invention and in some of the objects thereof, serve to control the signal output representing the various component color images. Output energy from the combining amplifier unit may then be supplied to a transmission channel (not shown) via the connecting link 121. The transmission channel may be of either the radio transmission link or wire line transmission link where desired. Further, where it is desired, the output from the combining amplifier unit 93 may be fed through a second conductor 123 to a monitor 125, at which the transmission characteristics may be observed.

The monitor arrangement, herein represented only in schematic form, may comprise substantially the arrangement of the usual receiver instrumentalities, and thus the signal output from the combining amplifier unit 93, as it appears in the conductor 123, may serve, through appropriate controls, to modulate the intensity of an electron beam developed within a cathode ray image reproducing tube for instance. Such an image reproducing tube (not shown) is preferably one of the type wherein the luminescent screen or target area upon which the image appears is of such composition as to produce substantially a black and white image, and this image, when viewed through the rotary filter, such as that shown by Fig. 2 for instance, will provide the desired color image reproduction.

From what has been set forth, it is apparent that certain conclusions can be reached in connection with the positioning of the switch armature 101 of the various reversing switch units 75, 77 and 79 to such a position that the orthochromatic or key image tends to decrease the output energy from the various mixer amplifiers 95, 97 and 99 at the corresponding picture point, it being assumed, of course, that synchronous and cophasal scanning relationships are attained for all of the images representing the various component primary colors, as well as the orthochromatic or key image.

These conclusions are that in the image which is monitored or the image received at various receiving points, increased definition will be obtained because of the high delineatory capabilities of the ordinary black and white image reproduction, resulting, of course, from the transmission of the orthochromatic or key image signals in the proper sequence, in which registration problems are not material.

Next, it will be apparent that increased gradation ranges are obtainable in the observed received image because, in effect, the highlight brightness is increased by the use of the key image and the shadows are darkened in the component color images by the control action of the key image in the transmitter.

Lastly, it is possible to obtain, for substantially all conditions of operation, a predetermined maximum level of brightness which will not be exceeded by virtue of the action of the key image signal series controlling the output energy for the individual component color images. It thus becomes apparent that, under no circumstances, will the image receiver or reproducing tube be overloaded, and therefore a greater efficiency in image reproduction is achieved.

For reasons of simplicity, the disclosure hereinabove made does not provide or disclose arrangements whereby synchronization is established either between the scanning beam action in the scanning tube 27 and a corresponding image reproducing tube of either the monitor 125 or a receiver (not shown), nor does the disclosure hereinabove provide for arrangements whereby the filter disc 1 of the transmitter may be synchronous in its operation with the filter disc 11 of the monitor or the receiver. It is, however, to be understood that in either instance the discs may be driven by suitable synchronous motors, for instance, operating from the same power supply and the scanning beams may be controlled or deflected according to well known television technique through the generation and transmission of suitable synchronizing signals caused to follow in sequence each field of transmission and each line of signal energy transmission in each field. For simplicity of illustration, these features are not illustrated, although it is to be understood that such may be and should be added to what has herein been set forth. Where the discs 1 of the transmitter and 11 of the receiver are not to operate upon the same power supply, then it is apparent that the field synchronizing signal may be caused to control, in known manner, the operation of the driving motor of the receiver, so that synchronous operation is readily maintained.

In the arrangement hereinabove discussed, for instance, the reversing switch units 15, 77 and 79 have been diagrammatically illustrated as comprising a plurality of tubes with a switch element arranged to include both tubes in circuit, or to by-pass one tube, depending upon the desired polarity of output signal from the unit. It is, of course, apparent that this is one of many suitable forms of control units for the purpose. Other forms may be used without departing from the spirit and scope of what is herein disclosed, and consequently the diagrammatic illustration is to be regarded as purely illustrative.

Among the other forms of arrangements which may be used as the reversing switch arrangement, are, for instance, a single output tube whereby the output at the plate or anode may be used for one polarity of signal, and the output at the

cathode may be used for another polarity of signal. A tube of this form may be used merely by altering the position of the control switch, such for instance as the switch 101 schematically represented by Fig. 3. Likewise, various forms of volume control units may be provided in place of the potentiometer controls schematically represented as connected to the output of the various reversing switch units.

10 Further, it is to be understood that any representations of the mixer amplifiers and the delay circuits are purely and entirely schematic, since such instrumentalities are well known in the art and therefore the illustration is not in any way to be considered as limiting, but rather as purely illustrative.

In the arrangement of Fig. 4, a further modification of the invention has been provided. This may briefly be described as constituting a form 20 wherein the channel width to transmit the color image representation may be regarded as having been increased over that disclosed by Fig. 3, in that provision is made for separate channels to transmit simultaneously the image representations corresponding to the red, the green and the blue component color images, and, after a plurality of such image fields representing such colors have been transmitted, a key image field corresponding to an orthochromatic image may be 25 simultaneously transmitted over all of the several channels.

In the arrangement of Fig. 4 as it is diagrammatically represented by the schematic illustration, the light of the image (not shown) is adapted 30 to be directed along the optical path 131 and through the optical system 133, and thence, by means of a plurality of half-silvered mirrors 135 and 137, a portion of the light is permitted to 35 pass directly along the initial optical path 131 or in a direction at right angles thereto. The half-silvered mirror 135 thus permits the orthochromatic image rays 131 to split into two paths, of which the light reflected from the mirror surface 135 is directed along a path 136 into an image scanning tube 139 through an appropriate 40 filter 141 which is adapted to direct upon the mosaic electrode 143 of the image scanning or camera tube 139 a light image of red characteristics, for instance. The unreflected rays which 45 pass through the half-silvered mirror 135 are then directed along the path 145 to impinge upon the second half-silvered mirror 137, from which 50 a portion of the rays is directed along a path 147 and another portion of the rays is passed directly 55 through the half-silvered mirror surface 137 along a path 149.

It will be assumed, for instance, that the reflected rays traveling along the light path 147 impinge upon the mosaic electrode 151 of the camera or image scanning tube 153 after passing 60 through a filter 155 which is adapted to direct rays corresponding to the green image upon the mosaic electrode of the camera or image scanning tube 153. Likewise, the light rays passing along the light path 149 are adapted to enter the image scanning or camera tube 157 and to fall 65 upon the mosaic electrode 159 thereof after having passed through the light filter 161 which is adapted to segregate the blue image from the orthochromatic image directed along the light path 149. Thus, a light image is simultaneously 70 impressed upon all of the image scanning or camera tubes 139, 153 and 157, but the light image upon tube 139 is that corresponding to the red image; the light image upon the tube 153 is that

corresponding to the green image, and the light image upon the tube 157 is that corresponding to the blue image, assuming the selection of filters as hereinabove outlined.

Since light losses occur in the half-silvered mirrors 135 and 137, the density of the filters 141 and 155 is such as to compensate for the loss and make the general intensity of the optical image impinging upon the mosaic electrodes 143 and 151 of tubes 139 and 153 respectively substantially of the same order as that of the image cast upon the mosaic 159 of the camera or image scanning tube 157. In this manner, equalization of the outputs is reasonably well maintained.

The tubes 137, 153 and 157 have been illustrated in a most schematic form, but it is to be understood that the tubes are generally of the type illustrated in Fig. 3 by the image scanning tube 27, so that when the mosaic electrodes 143, 151 and 159 of all of these tubes are scanned by the usual cathode ray scanning beam, output signals will result which appear in the output conductors 161, 162 and 163 connected respectively to the collecting electrode of the mosaics. Accordingly, these output video signals are appropriately amplified in the amplifiers 164, 165 and 166, from which output energy is supplied to the several commutators 167, 168 and 169 by way of the commutator brushes 170, 171 and 172 connected respectively to the conductors 173, 174 and 175. The signal outputs in these respective conductors are those representative of the simultaneously scanned red, green and blue images.

The various commutator elements 167, 168 and 169 are appropriately driven from a suitable prime mover (not shown), so that they revolve in synchronism and co-phaseally.

Since it was assumed, from what was hereinabove stated, that the transmission of the signals representing the scanned images would take place in such a manner that three image fields representing different color images would be transmitted simultaneously and in a sequence of three to be followed by a single transmission of an orthochromatic image on all transmission channels, the commutators 167, 168 and 169 are provided with commutating segments 176 and 177 each respectively, which extend for substantially 270° of the periphery and 90° of the periphery with suitable insulating segments 178 and 178' separating each section of the commutator. The longer segment 176 of the commutator is connected to a second commutator ring 179 for each commutator, from which, by means of the brushes 180, 181 and 182, the respective red, green and blue image signals are derived to be fed to the separate transmitter amplifiers 184, 185 and 186 connected respectively thereto by way of the conductors 187, 188 and 189. The rings 179 have insulating segments (as shown) to correspond in position to the insulating segments 178 and 178' of the outer rings 176, 177, it being appreciated that the brushes are aligned (as schematically indicated). The smaller section 177 of each of the commutators is connected to an inner slip ring member 190, 191 and 192 from which energy is picked up by means of a series of brushes 193, 194 and 195 and then fed by way of the conductor 196 connected to all of the brushes 193, 194 and 195 to energize simultaneously all of the transmitter amplifiers 184, 185 and 186.

It accordingly is apparent that the transmitter amplifiers 184, 185 and 186 are separately

energized with the red, the green and the blue video signal components, respectively, during three-quarters of any unit time period corresponding, for instance, to the time to scan four picture fields. During the remaining one-quarter of the assumed unit time period, the various transmitter amplifiers are energized by the combined output of all of the camera or image scanning tubes 139, 153 and 157 as derived from the amplifiers 164, 165 and 166, so that the signal energy appearing on the conductor 196, for instance, is that corresponding to an orthochromatic image, and thus, over each channel corresponding to the various colors chosen, there will be transmitted signals both of individual color and of the combined color representing the three selected components. The output from the various transmitter amplifiers 184, 185 and 186 is then fed by way of conductors 197, 198 and 199, for instance, to any suitable form of transmission channel, such as a radio link or a wire line transmission link, or to a suitable monitor instrumentality.

It has not been shown by the diagrammatic representation of Fig. 4, but is to be understood that scanning beams in all of the tubes 139, 153 and 157 for scanning the respective mosaic electrodes thereof are to operate simultaneously so as to strike the various mosaic elements in substantially identical spacial relationships. Each scanned raster is to be homologous and equidimensional. To this end, it is preferable to provide a single source of beam deflecting energy to be applied to deflect the cathode ray beams, in order that synchronous and co-phaseal relationship shall be maintained between each. It is, of course, to be understood that to achieve this objective it is desirable that the geometry of the scanning tubes substantially coincides, and that the applied operating voltages to each tube likewise substantially correspond in order that the general operating parameters for all the scanning tubes shall be alike. This, however, forms no specific part of the present invention except insofar as it co-operates with the remaining elements to produce the complete system. The arrangement for obtaining controlled movements of the scanning beams will be discussed more particularly in a companion application, Ser. No. 548,238, which was filed Aug. 5, 1944.

It is to be appreciated, in the arrangement illustrated by Fig. 4, that what is herein termed an orthochromatic or key image is merely one of several forms which might be used and represents one acceptable form. Other forms of key images may be derived from signal output of separate image pickup or camera tubes receiving the light image from any of the optical paths 131, 137, 145 and 149 prior to the time when the light of the images has passed through any filter. The key image signals thus derived may, as heretofore stated, correspond to the visual luminosity response, or to ultra-violet, or infra-red versions of the image which is picked up, or to any other selected form of key image signal. In any of these cases, such key image signal will be used identically in the manner hereinbefore set forth, that is, such key image signals will be impressed upon the conductor 196 and thus caused to energize all of transmitter amplifiers and channels during the period corresponding to the passage of such segments as 177 under the corresponding contact brush.

It is thus apparent, from what has been pointed out, that the system of Fig. 4 is a modifica-

tion which provides for simultaneously transmitting the red, the green and the blue component color images for simultaneous reproduction at receiving or monitoring points, and then, after a predetermined number of image fields has thus been transmitted, an equalized transmission, representing the combined red, green and blue component pictures, which corresponds to the key picture of Fig. 3, will be transmitted and reproduced at receiving points for a time period of 10 one image field, after which the sequence is repeated again and again. Thus, the system of Fig. 3 may be termed a combined simultaneous and cyclic method, since it is a simultaneous method for the separate color transmissions but cyclic between the color images and the key image.

For receiving the images transmitted by the arrangement of Fig. 4, various arrangements may be provided which would consist, for instance, of a single electron tube having a laminated luminescent target which would respond to reproduce the various picture colors, and in which the laminations would be so located that independent electron guns within the receiving cathode ray tube might operate to direct scanning beams thereagainst, or, alternatively, the system may be of the type disclosed by my applications, Ser. Nos. 548,238 and 548,239, each filed Aug. 5, 1944, and each relating to color television. Further, as known in the art, the receiving instrumentality may comprise a plurality of separate cathode ray image reproducing tubes individually having target areas adapted to reproduce the red, the green and the blue images and arranged to direct the issuing light simultaneously upon a single viewing target area at which the light image of all tubes is superimposed.

In a further alternative form, the receiver instrumentality, which is not herein specifically illustrated since it does not form a specific part of the invention except insofar as it is necessary to a complete understanding of the invention, will be assumed to comprise a plurality of separate cathode ray image reproducing tubes each being adapted to reproduce a pure black and white image and having a filter disc coordinated with each, with the filter disc of the respective channels being formed according to the arrangement of Fig. 2, except that for one channel all of the areas 13, 15 and 17 would, for instance, be adapted to produce a red image, whereas for the second channel, all of these areas would be adapted to produce a green image, and for the third channel, these areas would be adapted to produce a blue image.

Synchronization between the scannings of the receiver and the transmitter for the system last described is, of course, to be maintained in known ways, such, for instance, that described in connection with the description of Fig. 3, and therefore has not been herein illustrated in detail.

In a further modification of the invention, not herein illustrated, provision may be made for both simultaneous and cyclic transmission of the image fields, in that the red image may first be transmitted for one field, the green image then may be transmitted to follow for a second field, and the blue image caused to follow for the third field, after which these three image fields are simultaneously transmitted in equalized brightness to provide a corresponding key image or orthochromatic reproduction, and thus the reproduction of the images at the receiver is a cyclic series of red, green and blue images, for instance, followed by a key image.

Accordingly, the method last described is cyclic, insofar as the succession of the red, the green and the blue and the key images is concerned, but it is simultaneous so far as the production of the key image by the concurrent transmission and reception of the red, the green and the blue equalized brightness images is concerned.

In still a further form, the red image, the green image and the blue image may be simultaneously transmitted and received to produce the color image, and then the equalized red, green and blue images, corresponding to the key image, may be cyclically transmitted so that their reception, in succession, will produce the necessary key images. Such a method, not herein illustrated, is simultaneous so far as the tricolor image is concerned, but cyclic so far as the key image is concerned.

Further, in connection with the arrangement 20 herein described in connection with Fig. 4, it is apparent that if the choice of time duration for transmitting the color images, such as those representing the red, the green and the blue images, is made equal to a time period required to scan 25 and transmit one image field only, then appropriate time delay means, similar to that disclosed in connection with Fig. 3 and particularly the delay circuit 69 thereof, may be combined with the transmitter amplifiers 184, 185 and 186 to 30 provide the key image transmission, but otherwise the transmission should be of the general form hereinabove outlined.

It will be appreciated that while mechanical 35 commutation has generally been illustrated in Figs. 3 and 4 as representative of the principles of the invention and for the purpose of indicating the switching operations, an all-electric switching method may readily be utilized. Such circuits are well known in the art as illustrated, for instance, by patents heretofore granted to C. C. Shumard, No. 2,146,862, and C. S. Roys and H. F. Mayer, No. 2,089,430, as well as the application of Whitaker, Serial No. 436,983, filed March 31, 1942, for an invention entitled "Electrical circuits."

It will also be readily apparent to those skilled 40 in the art that the application of the key image to simultaneous color television transmission systems usually makes the delay networks unnecessary and requires an additional transmitting tube with an appropriate optical system and filter at the transmitter and an additional receiver tube without a filter and with an appropriate optical system to combine the black and white key image simultaneously with the primary red, green 45 and blue component images.

Having described my invention, what I claim is:

1. The method of color television transmission 50 which comprises the steps of producing groups of signals representative of predetermined additive primary colors of the object whose image is to be reproduced, producing a series of signals proportionate to the luminous emission of the colors of the object, and energizing a transmission channel by all of the produced series of signals.

2. The method of color television transmission 55 which comprises the steps of producing an independent series of signals representative of each of a plurality of predetermined primary colors of the object whose image is to be reproduced, producing a further independent series of signals representative only of the visual brightness of the colors of the object, and sequentially transmitting 60 all of the produced series of signals.

3. The method of color television transmission which comprises the steps of producing an independent series of signals representative of each of a predetermined plurality of primary colors of the object whose image is to be reproduced, producing a further independent series of signals by combining all of the series of signals so that the last independent series of signals is representative of the intrinsic brightness of the colors of the object, and transmitting all of the produced series of signals in sequence.

4. The method of color television transmission which comprises the steps of producing groups of signals representative of predetermined primary colors of the object whose image is to be reproduced, producing a series of signals representative only of the intrinsic brightness of the colors of the object, and cyclically energizing a transmission channel by all of the produced series of signals.

5. The method of color television transmission which comprises the steps of producing independent series of signals each representative of one of a predetermined plurality of additive primary colors of the object whose image is to be reproduced, producing a further series of signals representative of a key image of a brightness proportionate to the luminous emission of the object whose image is to be reproduced, and supplying all of the produced series of signals to a communication channel.

6. The method of color television transmission which comprises the steps of producing independent series of signals each representative of one of a predetermined plurality of additive primary colors of the object whose image is to be reproduced, producing a further series of signals representative of a key image of the object whose image is to be reproduced, controlling the signal level of the independent series of signals by the key image signals, and then transmitting all of the produced series of signals in sequence.

7. The method of color television transmission which comprises the steps of producing groups of signals representative of a plurality of predetermined additive primary colors of the object whose image is to be reproduced, producing a series of signals representative only of the intrinsic brightness of the colors of the object, controlling the signal level of the signals representing primary colors under the influence of the signals representing intrinsic brightness, and cyclically transmitting all of the produced series of signals.

8. The method of color television transmission which comprises the steps of producing a plurality of independent series of signals individually representative of predetermined selected additive primary colors of the object whose image is to be reproduced, producing a further independent series of signals representative only of the intrinsic brightness of the colors of the object, substantially uniformly controlling the signal level of the plurality of series of signals under the influence of the last named series of signals, and then transmitting all of the produced series of signals.

9. The method of color television transmission which comprises the steps of producing a plurality of series of signals each representative of one of a plurality of predetermined primary colors of the object whose image is to be reproduced, producing a series of signals representative of a key image of the object whose image is to be reproduced, and cyclically transmitting all of the produced series of signals.

10. The method of reproducing color television images which comprises the steps of receiving a series of signals representative of a plurality of predetermined additive primary colors, each series corresponding to the object whose image is to be reproduced, receiving a series of signals representative of a key image, additively colored images from the received signals representative of the separate primary color images, producing a black and white image from the signals representative of the key image, and combining all of the produced images.

11. The method of transmitting and receiving color television images which comprises the steps of producing a plurality of series of signals each representative of one of a predetermined plurality of additive primary colors of the object whose image is to be reproduced, producing a series of signals representative only of the intrinsic brightness of the colors of the object, transmitting all of the produced series of signals, receiving all of the transmitted signals, producing color images corresponding to the signals of the primary colors, producing a black and white image corresponding to the signals representative of the intrinsic brightness of the object, and additively combining all of the produced images.

12. A method of color television comprising producing a plurality of independent series of signals representing in sequence a predetermined plurality of primary colors of an image, producing after a predetermined number of series of signals representative of primary colors an independent series of signals representative of the intrinsic brilliance of all colors of the image, independently amplifying the signals of each of the series produced, controlling the sequence of amplification to coincide with the production of the individual series of signals, deriving a control series of signals by delaying the signals representative of the brightness of the image for periods which are multiples of the scanning field period for controlling the amplification level of each of the independent series of signals, and then combining all of the produced series of signals for transmission sequentially.

13. A system of color television which comprises scanning means for producing a plurality of independent series of signals each representative of one of a plurality of predetermined primary colors of an object whose image is to be reproduced, means to produce an independent series of signals representative of a key image of the object whose image is to be reproduced, and distributor means for cyclically transmitting all of the produced series of signals.

14. A system of color television which comprises a scanning device and filter means for producing a plurality of independent series of signals each representative of one of a plurality of predetermined primary colors of an object whose image is to be reproduced, means operative upon completion of the production of the series of signals representative of the primary color images to reveal to the scanning means an orthochromatic image of the object so as to produce from the scanning means an independent series of signals representative of a key image of the object whose image is to be reproduced, and distributor means for cyclically transmitting all of the produced series of signals.

15. A system of color television which comprises scanning means for sequentially producing independent series of signals individually representative of different ones of selected primary colors.

of an object whose image is to be reproduced, means for producing, following the aforesaid sequences of signals, an independent series of signals representative of a key image of the object whose image is to be reproduced, distributor means for sequentially transmitting all of the produced series of signals, and means for modifying the transmission of each series of signals representing the predetermined primary colors under the control of the series of signals representing the key image.

16. In a color television system, a scanning and co-operating filter means for analyzing an optical image to produce a plurality of independent series of signals representing in sequence predetermined primary colors of the image, means to produce from the scanning device, following a predetermined number of series of signals representative of primary colors, an independent series of signals representative of the intrinsic brilliance of all colors of the image, and means for combining all of the produced series of signals for energizing a transmission line sequentially by the independent series of produced signal energy.

17. In a color television system, a camera tube, an optical filter for revealing light of different primary colors sequentially to the tube, said camera tube providing a means for analyzing an optical image to produce a plurality of independent series of signals representing in sequence predetermined primary colors of the image, means to produce from the camera tube, following a predetermined number of series of signals representative of primary colors, an independent series of signals representative of the intrinsic brilliance of all colors of the image, and means for combining all of the produced series of signals for energizing a transmission line sequentially by the independent series of produced signal energy.

18. In a color television system, an image scanning tube, filter means for revealing to said tube in sequential manner light of a plurality of primary color images and an orthochromatic key image, means for analyzing the light images revealed to the tube to produce a plurality of independent series of signals representing in sequence the several primary color and key light images, independent amplifier means for amplifying the signals of each of the produced series, distributor means for controlling in sequence the energization of one only of the several amplifiers, and means for combining all of the produced series of signals for energizing a transmission line sequentially by the independent series of produced signal energy.

19. In a color television system a camera tube and co-operating filter means for analyzing an optical image to produce a plurality of independent series of signals representing in sequence predetermined primary colors of the image, means to produce from the camera tube, following a predetermined number of series of signals representative of primary colors, an independent series of signals representative of the intrinsic brilliance of all colors of the image, independent amplifier means for amplifying the signals of each of the series produced, distributor means for controlling in sequence the energization of each of the several amplifiers, and means for combining all of the produced series of signals for energizing a transmission line sequentially by the independent series of produced signal energy.

20. In a color television system, a camera tube and co-operating filter means for analyzing an optical image to produce a plurality of independ-

ent series of signals representing, in sequence, a predetermined selected number of primary color versions of the optical image, means to produce from the camera tube, following a predetermined number of series of signals representative of primary colors, an independent key series of signals representative of the intrinsic brilliance of all colors of the image, independent amplifier means for amplifying the signals of each of the series produced, distributor means for controlling, in sequence, the energization of the several amplifiers so that one only is instantaneously energized, a plurality of delay circuits, means to energize the delay circuits by the signals representative of the brightness of the image, means for controlling the amplification level of the amplifiers for each of the independent series from the delay circuit, and means for combining all of the produced series of signals for energizing a transmission line sequentially by the independent series of produced signal energy.

21. In a color television system, an image scanning tube, filter means for revealing to said tube in sequential manner light of a plurality of primary color images and an orthochromatic key image, means for analyzing the light images revealed to the tube to produce a plurality of independent series of signals representing in sequence the several primary color and key light images, independent amplifier means for amplifying the signals of each of the produced series, distributor means for controlling in sequence the energization of one only of the several amplifiers, means including a plurality of delay circuits energized by the signals representative of the brightness of the key image for controlling the amplification level of the amplifiers for each of the independent series, and means for combining all of the produced series of signals for energizing a transmission line sequentially by the independent series of produced signal energy.

22. In a color television system, an image scanning tube, filter means for revealing to said tube in sequential manner light of a plurality of primary color images and an orthochromatic key image, means for analyzing the light images revealed to the tube to produce a plurality of independent series of signals representing in sequence the several primary color and key light images, independent amplifier means for amplifying the signals of each of the produced series, distributor means for controlling in sequence the energization of one only of the several amplifiers, means for deriving from the key image a control signal for controlling in the sequence of scanning the amplification level of each of the amplifiers for amplifying each of the chosen primary colors, said means comprising a plurality of delay circuits having individual time delay periods proportional to the time delay between the production of each controlled series of signals representing a primary color from the time of production of the key image signals, reversing switch means for causing the polarity of the signal applied to control the amplification in the amplifier means to coincide with or oppose the polarity of the signals representing the different primary color images, and means for combining all of the produced series of signals for energizing a transmission line sequentially by the independent series of produced signal energy.

23. A color television system comprising an electronic camera tube having means for projecting an optical image thereon, filter means interposed in the path of the optical image directed

19

upon the said camera tube for illuminating the said scanning tube in sequence by images of predetermined selected primary colors followed by a key image representing the general over-all brilliance of the optical image, a plurality of signal amplifier means of a number equal to the number of primary colors and the key picture, distributor means for cyclically and sequentially energizing individual amplifiers of the plurality by one only of the plurality of series of signals representing the selected primary color images and the key image, a combining circuit for combining all of the produced images, means for deriving from the key image a control signal for controlling the amplification level of the amplifiers for amplifying each of the chosen primary colors, said means comprising a plurality of delay circuits having time delays equal in sequence to integrals of the time period required to produce each of the controlled series of signals representing a primary color, reversing switch means for controlling the polarity of the signal applied to control the amplification in the amplifier means, and means for applying all of the signals to a transmission channel.

24. The method of additive color television transmission which comprises the steps of producing independent series of signals representative of selected predetermined primary colors according to which the object whose image is to be reproduced is to be analyzed, producing a further independent series of signals representative only of the combined intrinsic brightness of the spectral colors of the object, and consecutively transmitting all of the produced series of signals. 30

25. In an additive color television system a plurality of sources of video signals individually cor-

10

responding to selected component color images and to a key image of an object or scene respectively, means for continuously controlling within their amplitude range each element of the component color signals in accordance with the spatially homologous portion of the key image signals, and means to energize a transmission channel by each of the resulting component color image signals and the key image signals.

26. The method of additive color television transmission which comprises the steps of producing groups of signals representative of predetermined primary colors of the object whose image is to be reproduced, producing a series of key image signals representative only of the visual brightness of the colors of the object, and energizing at least one transmission channel by all of the produced series of signals.
